UNITED STATES PATENT OFFICE

145,527

DESIGN FOR A DESCENT RETARDER

Paul M. Lewis, Los Angeles, Calif., assignor to Sky-Hook Co., Los Angeles, Calif., a limited partnership of California

Application February 12, 1945, Serial No. 117,890

Term of patent 3½ years

(Cl. D34—15)

To all whom it may concern:

Be it known that I, Paul M. Lewis, a citizen of the United States, residing in Los Angeles, in the county of Los Angeles and State of California, have invented a new, original, and ornamental Design for a Descent Retarder, of which the following is a specification, reference being had to the accompanying drawing, forming part thereof.

Fig. 1 is a top perspective view of a descent retarder, showing my design.

Fig. 2 is a bottom perspective view.

Fig. 3 is a top plan view.

Fig. 4 is an end elevational view, looking toward the right in Fig. 3.

Fig. 5 is a broken elevational view, looking from the bottom in Fig. 3.

I claim:

The ornamental design for a descent retarder, substantially as shown.

PAUL M. LEWIS.
